Specification for Design.

Patented June 22, 1909.

Application filed February 19, 1909. Serial No. 479,009. Term of patent 7 years.

● *To all whom it may concern:*

Be it known that I, LORENZ KILLIAN, a citizen of the United States, residing at Brooklyn, in the county of Kings and State of New York, have invented a new, original, and ornamental Design for a Chair; and I do hereby declare the following to be a full, clear, and exact description of the same, reference being had to the accompanying drawing, forming a part thereof.

The design comprises the general outline of the chair together with the ornamental

carving of the front legs, the back uprights, the curved top extending between the back uprights as well as the shape and curvature of the rear legs and the ornamental framework between the legs.

I claim:—

The ornamental design for a chair as shown and described.
